CLAIM

The ornamental design for a small space odor neutralizer, as shown and described.

DESCRIPTION

FIG. 1 is a top and side perspective view of the small space odor neutralizer showing our new design in its closed position, the opposite side being substantially identical except for the helical line pattern which would be reversed; FIG. 2 is a top plan view thereof; FIG. 3 is a front elevational view thereof; FIG. 4 is a rear elevational view thereof; FIG. 5 is a bottom plan view thereof; and, FIG. 6 is a front elevational view showing our small space odor neutralizer in its open position.
